US00D711738S

(12) **United States Design Patent**
Scott

(10) **Patent No.:** US D711,738 S
(45) **Date of Patent:** ** Aug. 26, 2014

(54) **BOX**

(71) Applicant: **William Mitchell Scott**, Villa Hills, KY (US)

JP JP 52-171526 12/1977
7-35313 6/1995

(72) Inventor: **William Mitchell Scott**, Villa Hills, KY (US)

(Continued)

(**) Term: **14 Years**

(21) Appl. No.: **29/456,352**

(22) Filed: **May 30, 2013**

(Continued)

FIG. 1 is an exploded perspective view of the box;
FIG. 2 is an exploded side view of the box, the opposite side being a mirror image;

FIG. 3 is another side view of the box in a closed configuration, the opposite side being a mirror image;

FIG. 4 is an exploded rear view of the box;

FIG. 5 is an exploded front view of the box;

FIG. 6 is a perspective view of the box in a closed configuration;

FIG. 7 is a top view of the box; and,

FIG. 8 is a bottom view of the box.

The broken lines shown in the drawings depict environmental features that form no part of the claimed design.

1 Claim, 7 Drawing Sheets
